UNITED STATES PATENT OFFICE.

EDWARD D. NEWINGER, OF SOUTH BEND, WASHINGTON.

SKIDWAY.

1,320,408.

Specification of Letters Patent.

Patented Nov. 4, 1919.

Application filed June 21, 1918. Serial No. 241,188.

To all whom it may concern:

Be it known that I, EDWARD D. NEWINGER, a citizen of the United States, residing at South Bend, in the county of Pacific and 5 State of Washington, have invented certain new and useful Improvements in Skidways, of which the following is a specification.

This invention relates to improvements in loading devices and it is the principal object 10 of the invention to provide a novel form of skid way for use in loading lumber or heavy timbers on railway cars and other vehicles, whereby the same can be moved therealong in a step-by-step fashion until on the vehicle 15 without liability of slipping, thus, eliminating the use of cranes and similar loading devices now commonly employed.

Other objects will be in part obvious and in part pointed out hereinafter.

20 The improvements in the details and arrangement of parts will be apparent from an inspection of the accompanying drawings, in connection with the specific description hereinafter contained, and wherein the 25 preferred embodiment of the invention is disclosed for the purpose of imparting a full understanding of the invention.

In the drawings:

Figure 1 is a fragmentary side elevation 30 of one of the improved skid ways, a portion of the same being broken away and shown in section,

Fig. 2 is a vertical transverse section therethrough, and

Fig. 3 is a fragmentary top plan view of one end of the same.

Having more particular reference to the drawings, in connection with which like reference characters will designate corresponding parts throughout the several views, the improved skid way comprises a body member composed of a pair of channelled arms 1 arranged in parallel relation and connected by bolts 2 throughout their length.

45 Other bolts 3 are passed through portions of the channelled arms 1 at spaced intervals throughout their lengths and receive bearing sleeves 4 thereon on which stops 5 are pivotally arranged. In this connection, it 50 is to be noted that certain of the bolts 2 serve as forms of stops for the pivotal stops 5, that is, engaging the same intermediate their ends and in this limiting upward movement thereof. To normally maintain

the pivotal stops 5 in their uppermost positions with relation to the body member, springs 6 are arranged about the various bearing sleeves 4 and have certain of the ends thereof curved and engaged with the adjacent bolts 2 as at 7 while the remaining 60 ends are provided with lateral extensions which are engaged with adjacent portions of the pivotal stops 5 as at 8. Obviously, the stops 5 in this way will be normally maintained in positions adjacent their respective 65 stop bolts 2 and as a consequence, will afford effectual stops for the lumber or timbers being moved over the skid way, thus, preventing the slipping of the same as it is advanced thereover in a step-by-step fashion. 70

Spurred feet 9 are connected to the outer faces of the lower ends of the channelled bars 1 by passing bolts 10 therethrough and as will be appreciated, provide means whereby the lower end of the skid way can be fixedly 75 engaged with the ground or other surface on which it is arranged, while the upper end thereof is placed on a portion of a railway car or other vehicle receiving the logs, lumber or timber.

80 In using the improved skid way, the timbers are rolled onto the same by means of crowbars and peavey, or if desired, by a chain or wire cable running over a suitable guide means and engaged with the timbers. 85 The timber is advanced over the skid way in a step-by-step fashion and, as the same moves over the various stops 5, said stops will of course be depressed against the tension of the springs 6. As the timber passes 90 the stops, they will of course immediately move to their uppermost positions and in this way serve to prevent the slipping of the timber from the skidway during its movement thereover.

95 From the foregoing, it will be readily understood by persons skilled in the art that I have provided an exceedingly efficient and simple form of skid way and one which will eliminate the use of cranes, derricks and 100 other similar loading appliances now commonly used for placing timber on cars, boats and other vehicles. Furthermore, the skid way is of such construction as to permit the moving of the same from place to 105 place as may be desired.

Manifestly, the construction shown is capable of considerable modification and such

modification as is within the scope of my claims, I consider within the spirit of my invention.

I claim:

- 5 1. A device of the character described including a pair of arms, connecting elements arranged transversely thereof for maintaining the arms in spaced parallel relation to each other, stops pivotally mounted on the connecting elements, limiting elements arranged between the arms and positioned forwardly of the connecting elements, and spring members embracing the connecting elements and having their terminals embracing the limiting elements and the stops and tensioned to yieldingly maintain the stops against the limiting elements.
- 10 2. A device of the character described including a body member composed of spaced parallel channeled arms, bolts passing

through said arms at intervals throughout their lengths for connecting the arms together, bearing and spacing sleeves arranged about said bolts positioned between the arms, stops having their inner ends 25 pivotally arranged about the sleeve, limiting bolts passing through the arms and arranged in proximity to the connecting bolts and above and forwardly thereof and spring members having their medial portions 30 embracing the bearing sleeve and the terminals of the side portions respectively embracing the adjacent limiting bolts and lower faces of the stops so as to normally yieldingly hold the upper faces of the stops against the 35 limiting bolts and at an inclination to the arms.

In testimony whereof, I affix my signature hereto.

EDWARD D. NEWINGER.
